Samuel J. Steinman, New York, N. Y.

Application March 8, 1939, Serial No. 83,426

Term of patent 3½ years

To all whom it may concern:

Be it known that I, Samuel J. Steinman, a citizen of the United States of America, residing in city of New York, county of New York, and State of New York, have invented a new, original, and ornamental Design for Combined Billfold, Change Purse, and Key Holder, of which the following is a specification, reference being had to the accompanying drawing, forming part thereof.

Fig. 1 is a front view of a combined billfold, change purse, and key holder showing my new design.

Fig. 2 is a plan view in open position.

Fig. 3 is an edge view thereof.

I claim:

The ornamental design for a combined billfold, change purse, and key holder substantially as shown.

SAMUEL J. STEINMAN.
